JAMES WHITELAW, OF ST. LOUIS, MISSOURI.

STOP MECHANISM FOR SEWING-MACHINES.

1,191,635.

Specification of Letters Patent.

Patented July 18, 1916.

Application filed August 27, 1914. Serial No. 858,807.

To all whom it may concern:

Be it known that I, JAMES WHITELAW, a citizen of the United States, residing at St. Louis, in the State of Missouri, have invented certain new and useful Improvements in Stop Mechanism for Sewing-Machines, of which the following is a specification.

My invention relates to stop motions, and in some of its features particularly to a sewing-machine stop-motion and power-transmission construction.

One of the objects of my invention is to provide a stop motion which will bring the moving parts to rest in a position that is substantially invariable, regardless of the velocity that the parts may have had prior to the stopping action, and that will effect its operation without injurious jar or shock to the arrested mechanism.

20 A further object of my invention is to provide a construction of the character described employing jointly and co-operatively a yielding, self-returning stop-member and a brake actuated thereby, both acting on the parts to be arrested, so that the progression of the moving parts past the cyclic point in their movement where the stopping devices are thrown into action is short, and the arrested parts are spring-returned to their position of rest.

Another object of my invention is to simplify and improve the construction of stop motion devices for sewing machines and the like by novel correlation of clutching, stopping, stop-timing and operating mechanisms; and to improve in construction the elements and sub-combinations thereof.

In the drawings wherein I have illustrated a single embodiment of my invention as applied to a sewing machine, for purposes of full disclosure, Figure 1 is an illustration, diagrammatic in parts, of a sewing machine, equipped with stop-motion and power transmission means embodying my invention; Fig. 2 is an extended perspective of the stop-motion and clutch parts; Fig. 3 is a vertical, longitudinal section therethrough; Fig. 4 is a perspective detail of a clutch part; Fig. 5 is a perspective detail of a connector part; Figs. 6, 7 and 8 are sections on lines 6-6, 7-7 and 8-8 of Fig. 3; Fig. 9 is a section on line 9-9 of Fig. 1.

In the drawings 10 indicates the main shaft of a sewing machine and 11 the fixed bearing at its power receiving end, beyond which the shaft projects to receive the stop

motion and clutch devices. In the particular construction shown, a block 11 is keyed at 12 to the shaft to rotate therewith. It carries, relatively, the axially shiftable 60 means that throws into action the power-wheel clutch and the shaft-arresting means. The axially shiftable connector shown is a stiff bar or key, 13, slideable axially in a groove 14 provided therefor in block 11 and 65 shiftable by the bell crank shifter-lever 15, through the intermediary of the conventional shifter yoke 16 and grooved shifter member or controller 17, the latter secured as by screw 18 to the shiftable bar 13. 70 When moved to the right, (Figs. 2 and 3,) the shiftable member or connector, 13, sets a clutch that connects power wheel 20 with the shaft 10; and when moved to the left said connector member throws the shaft- 75 stopping appliances into action.

Power wheel 20 is loosely mounted on the shaft 10 between the fast end collar 20^a and the fast block 11, said wheel having in its inwardly facing hub 20' an annular recess 21 80 receiving the reduced annular extension 11' of the block 11. In the annular clearance between the parallel surfaces of extension 11' and the outer wall of hub 20' is an expansible clutch-band 22 that rides in rotation with the fast block 11. In the particular construction shown the split clutch band 22, under normal tension, frees the power wheel 20, but it is expansible by the connector 13 to make fast frictional engagement 90 with the power wheel and so, through the clutch, the connector member and the block 11, to communicate motion to the shaft 10. Specifically the confronting end-walls 22' of the split clutch-ring converge outwardly 95 and in the wider portion of this tapered slit-space there normally lies the outer end of the connector member 13, so that the clutch-band is positively carried in rotation with the shaft 10 at all times. The walls of 100 the connector member confronting the converging walls 22' of the clutch member are recessed and provided with spring-positioned anti-frictional rollers 23, so that when the clutch member is moved to the right 105 said rollers, riding along the converging faces 22' expand the clutch-band. This condition is shown in Fig. 3.

It will be observed that by the specific construction shown I am able to provide a very 110 effectively-working friction clutch, operable on relatively short movement of the con-

necter-bar 13, adequately housed within the hub of the power wheel 20, and condensing the clutch parts within small compass.

Since the shifter member or controller, 5 17, rotates with the shaft, its inner end, extended to form sleeve 17' may conveniently be employed as a movable part of a friction brake for the shaft (though any fast part might be so employed). This brake-surface 10 17' receives a movable brake member, preferably in the form of a split band 25 having one end rigidly mounted, through standard 26 and bolt 27, on a suitable part of the machine frame, and at its free end, arranged 15 for compression-applying movement to be controlled by connector 13. Specifically the free end of the brake band carries a spring housing 30 recessed to receive a compression spring 31 through which the brake-setting pressure is applied. Through the housing and spring passes a rod 32 having at its upper end a head 33 and at its lower end, where it passes through the bottom of the housing, receiving the adjusting nut 34. 20 25 Obviously, downward pressure on head 33 will compress the spring and through the spring tension will tend to set the brake, and when the connector-member 13 is appropriately moved to the left it serves to 30 communicate power from the main shaft to the spring-head 33 to cause the depression of the spring-head.

As an intermediary between the controller member and the brake setting spring I preferably provide a striker member 40, and 35 preferably associate with said striker a timing member or guard structure 41 that insures proper co-action of the connector 13 and the striker. When permitted by the 40 guard 41, connector member 13 may positively engage the striker 40, to carry it in rotation and cause it functionally to act upon the brake-setting spring.

In the specific construction shown, striker 45 member 40 is a plate loose on the shaft 10 and interposed between the inner end of block 11 and the bearing block 6 or other appropriate part of the machine frame. The striker is capable of oscillatory movement to an extent limited by engagement 50 of a pin 42 on the machine frame in a slot 43 of the striker, and it has a laterally bent finger 44 overhanging the head 33 of the brake-applying spring, by which said 55 striker is normally held in raised position as shown in Figs. 7 and 8. The brake construction is so located that the spring stands substantially tangential to the path of movement of the striker-finger 44. At a suitable 60 point in its periphery the striker is provided with a notch 45 of suitable depth to receive a head 13' of the connector-member 13, and in rear of the notch the perimeter of the plate is cut down smaller than the maximum radius of head 13', as shown at 46. The an-

nular surface of said striker plate in the axial path of said head 13, is preferably tapered or gradually thinned in a spiral 47 leading downward into the notch 45. If the head 13' of the controller 13 be pressed 70 to the left, to make contact with the annular surface of the striker 40 a suitable time, or considerably number of degrees, before the controller reaches notch 45, said controller head will glide down the tapered 75 surface 47 and make positive, square engagement with the leading end 45' of the notch 45 so as to carry the striker rotatively with the shaft to compress the spring 32 and set the brake. It is important, however, in a 80 machine wherein the rotating parts move rapidly, as in a high speed sewing-machine, that provision be made to insure that the connector 13 shall either make good, substantial contact with the notch wall 45' or 85 shall not engage the notch at all; this to prevent battering up of the acting surfaces of the two parts, and other injury to the machine, by partial or ineffective engagement thereof. To this end the guard or 90 timer 41 is provided. In the specific construction shown said guard takes the form of a metal shield-piece pivoted between its ends, as at 50, to the extended finger of the striker, and acted on by a spring 51, interposed between its rear end and the striker, so that its forward or leading end, (which is preferably slightly thicker than the thickness of the striker member 40,) may normally rest upon the suitably-reduced perimeter 46 of the striker plate 40 partially 100 to close the notch 45. The receiving end 52 of the guard is curved outwardly so that its end is located radially beyond the rotative path of head 13' of the connector, and 105 is provided with a tooth 53 with its receiving surface inclined and its front edge squared, spaced apart from the wall 45' of the striker by the width of connector-head 13'. Consequently, if the key or connector 110 13 be moved to the left to function with the striker at a time, in the rotation of the main shaft, before its head 13' axially registers with the guard member 41, the connector-head, following down the inclined surface 47 115 of the striker, will pass freely under the receiving end of the guard, and, coöperating with the inclined portion 52 of the guard, will tilt the guard outwardly so that obviously the connector head may proceed uninterruptedly under the tooth 53 and into engagement with the notch 45 of the striker. In such positoin it is fixed in relation to the striker, by wall 45' on the one side, tooth 53 on the other. But if the connector head 120 has passed rotatively beyond the receiving end 52 of the guard 41 before the effort is made to engage the connector with the striker plate, then, as indicated in dotted lines in Fig. 8, the side surface of the guard 125 130

is axially interposed in the way of the connector head and said head is unable to penetrate into the notch 45, but slides along the side surface of the guard post notch 45 without making effective engagement with the striker. Of course when the operator is thus trying to stop the machine the next revolution of the main shaft will bring about the desired result.

10 My stop motion construction may, of course, be applied to many forms of sewing machines and many machines for other purposes, and its shifter yoke, or equivalent part, may be operated in any suitable 15 fashion. In Fig. 1, however, I have shown diagrammatically parts of a machine for blind stitching of the general type known as the "Lewis" machine, and in said illustration *p* represents diagrammatically a rigid 20 presser foot, *w* a movable work handling mechanism below the presser foot, susceptible of being depressed against the tension of spring *s* to permit insertion of the work. In such installations I prefer that the 25 connections for operating the stop motion controller be combined with the connections for operating the work handling mechanism, and in the specific construction shown the bell crank shifter lever 15 has link connections 30 30 with a rocking gate 61 pivotally carried by a longitudinal shaft 62 of the machine, said gate having a lever arm 63 extending therefrom in the path of movement of a rocker 64 that also works on spring *s* to control de- 35 pression of the work handling mechanism *w*, said rocker being provided with a connection 67 extending to any suitable lift or foot treadle. A spring 69 interposed between the bell-crank shifter-lever 15 and the part of 40 the frame will tend normally to throw the controller to the left to disengage the clutch from the power wheel. Consequently when link 67 is in neutral position the machine is at rest, but by raising or lowering the link as 45 the case may be the operator may either depress the feed or throw in the clutch.

Briefly to review the operation of the device as specifically described, when the connector member 13, rotatable with, but slide- 50 able axially on, the main shafts, is thrown to the right, its antifrictional rollers 12 spread the band clutch 22 making effective clutch engagement with the power wheel 20 so that power is applied to the main shaft 10. When 55 the slideable connector or key 13 is moved to the left during such part of the cycle of rotation of the main shaft that the head 13' of the connector may not strike upon the side surface of the timer guard 41, the left end 60 of the connector will follow the incline 47 of the striker plate, 40, moving the guard 41 on its pivot, and the connector end will make positive engagement in the notch 45. When 65 the shaft is thus freed from the clutch and positively connected with the striker 40, it

carries the latter around through a few degrees of rotation, the finger 44 of the striker acting on spring head 33 to compress the spring 32 that is carried by the brake band. This action I have found in practice to be 70 highly effective. By the combined action of the yielding spring and the friction brake the shaft is stopped substantially without jar or shock injurious to the machine. Of course the higher the speed of the machine 75 the further the spring will be compressed and the quicker will the spring band be applied; but when the spring has acted and has received its compression, it returns the striker to its normal position, turning the 80 shaft backward a few degrees. The return movement of the striker is limited by slot 43, and it will be noted, tooth 53 prevents overthrowing of the shaft due to the back-kick of spring 32 so that the shaft-stoppage is 85 uniform, and its final position of rest is the same whatever may have been its running velocity. In a sewing machine, of course, this position at which the shaft is stopped is such that the needle is out of the goods, so 90 that when the work handling devices are properly positioned the goods may be free for manual movement.

Having described my invention, what I claim is:—

1. In a stop motion for stopping a shaft at a predetermined rotating position, the combination with brake means for the shaft, of a spring coöperating with said brake to set the brake when the spring is tensioned, a 100 part for coaction with the spring movable rotatively with the shaft to tension spring, means for effecting coöperation of said part and spring and means to prevent initiation of such coöperation during a pre- 105 determined interval in the shaft-cycle.

2. In a stop motion, the combination of a rotatable shaft, a loose striker, a spring for opposing rotation of said striker, means carried in rotation by the shaft, axially shift- 110 able thereon to engage or disengage said striker, and means to prevent engagement of said shiftable means and the striker during a predetermined portion of the cycle of rotation of the shaft.

3. In a stop motion of the character de- 115 scribed, the combination of a shaft, brake means therefor including a band brake, and a brake setting compression spring, a striker loose on the shaft arranged for coöperation with said spring to compress said spring and set said brake when said striker is turned with the shaft, and means on the shaft, carried in rotation therewith, to move the striker, the last said means and the striker 120 relatively movable to engage or disengage them.

4. In a stop motion of the character de- 125 scribed, the combination of a shaft, brake means therefor including a band brake, and 130

a brake setting compression spring, a striker loose on the shaft arranged for coöperation with said spring to compress said spring and set said brake when said striker is turned 5 with the shaft, means on the shaft, carried in rotation therewith, to move the striker, the last said means and the striker relatively movable to engage or disengage them, and a guard member for preventing engagement 10 of said means with the striker during a predetermined portion of the rotating cycle of the main shaft.

5. In a device of the character described, the combination of a shaft, a loose power 15 wheel thereon having an inwardly facing recess, a split circumferentially expansible clutch-band within said recess rotatable with the shaft, shaft stopping means normally disconnected from the shaft, an axially 20 shiftable member carried in rotation by the shaft, movable in one direction to expand said clutch-band and in the other direction to actuate said stopping means.

6. In a stop motion, a shaft, a loose part, 25 means rotatively fast on the shaft axially shiftable thereon to engage said loose part; a compression spring arranged tangentially to said loose part to be compressed thereby, and a band brake for the shaft comprising 30 a split ring carrying a spring receiving socket at one end.

7. In a stop motion, a shaft, band-brake means therefor comprising a split compression band fast at one end and loose at the 35 other, and having a spring-socket at its loose end, a coiled compression spring carried by said socket, and means rotatable with said shaft for compressing said spring.

8. In a stop motion, a shaft, a band-brake 40 means therefor comprising a split compression band fast at one end and loose at the other, and having a spring socket at its loose end, a coiled compression spring carried by said socket, and means for compressing said 45 spring comprising a loose striker and a connector rotatable with the shaft and axially movable to engage or disengage the striker.

9. In a stop-motion, the combination of a shaft, a block fast thereon, a connector slideable in said block, a controller member fast 50 on said connector, a shifter lever for said controller, a band brake coacting with said controller member, a compression spring connected with the brake to set it when the spring is tensioned, and a striker loose on 55 the shaft, arranged to be engaged by the connector and, when so engaged, compress the spring.

10. In a stop motion for stopping a shaft at a predetermined rotating position, the 60 combination with brake means for the shaft, of a spring coöperating with said brake to set the brake when the spring is tensioned, a part for coaction with the spring movable rotatively with the shaft to tension the 65 spring, means for effecting coöperation of said part and spring, and means to prevent such coöperation during a predetermined interval in the cycle of shaft rotation commencing approximately a quarter revolution 70 in advance of the point of coöperation.

11. In a stop motion of the character described, the combination of a shaft, brake means therefor including a band brake, and a brake setting compression spring, a striker 75 loose on the shaft arranged for coöperation with said spring to compress said spring and set said brake when said striker is turned with the shaft, means rotatable with the shaft and axially movable to engage or disengage the striker, and a guard member pivoted to the striker and lying in the rotary path of the last said means for preventing engagement of said means with the striker during a predetermined portion of the ro- 80 tating cycle of the main shaft.

In testimony whereof I hereunto set my hand in the presence of two subscribing witnesses.

JAMES WHITELAW.
